UNITED STATES PATENT OFFICE.

CHARLES L. RAYFIELD, OF CHICAGO, ILLINOIS, ASSIGNOR TO BENEKE & KROPP MFG. CO., OF CHICAGO, ILLINOIS, A CORPORATION OF ILLINOIS.

TEMPERATURE-REGULATOR FOR INTERNAL-COMBUSTION ENGINES.

1,359,198.

Specification of Letters Patent. Patented Nov. 16, 1920.

Application filed October 8, 1917. Serial No. 195,490.

To all whom it may concern:

Be it known that I, CHARLES L. RAYFIELD, a citizen of the United States of America, residing at Chicago, in the county of Cook 5 and State of Illinois, have invented certain new and useful Improvements in Temperature-Regulators for Internal-Combustion Engines, of which the following is a specification.

10 My invention relates to improvements to compression operated temperature regulator for internal combustion engines, and the objects of my improvement are:

First, to provide a temperature regulator 15 for the cooling medium of an internal combustion engine;

Second, the production of a temperature regulator for the cooling medium of an internal combustion engine, operable by a 20 uniform, or variable fluid pressure which may result from the operation of the engine, or otherwise, and which may be employed in devices of sufficient magnitude to insure the proper functioning of the regulator under 25 disadvantageous conditions; and

Third, to afford a construction of the class which is controlled in its operation by thermo-responsive means which is not burdened with the work incident to the operation 30 of the mechanism, and may therefore be made more sensitive to temperature variations.

With the foregoing and other objects in view, my invention consists in the novel 35 features and in the novel combination and arrangement of parts illustrated in the accompanying drawings forming a part of this specification and particularly pointed out in the claims hereunto appended; it being understood that changes, variations and 40 modifications in the details of the invention within the scope of the claims, may be resorted to without departing from the spirit or sacrificing any of the advantages thereof.

45 In the drawings,

Figure 1 is a side elevation of an internal combustion engine, a radiator and connections, with my improved cooling medium temperature regulator in the circulating 50 system,

Fig. 2 is a longitudinal central section of the temperature regulator and its housing.

Similar numerals refer to similar parts throughout the several views.

In the embodiment chosen, one circulating system for the cooling medium comprises an internal combustion engine or heater 3 having a water jacket 4 intake manifold 5, the usual exhaust manifold (not shown) water manifold 6, radiator or cooler 60 7, pump 8, flexible tubing 9, between the delivery end of the radiator and the intake of the pump 8, and flexible tubing 10 connecting the delivery end of the pump 8 with the water jacket 4 of the engine 3. A flexible tube 11 connects the water manifold 6 with nipple 12 of conduit 13 which is provided with by pass nipple 14 and delivery nipple 15. The flexible tubing 16 unites the upper end of the radiator with the nipple 15. 70

The by pass 17 preferably is of flexible tubing attached at one end to the nipple 14 and at the other end to the intake end of the pump 8.

No limitation is made to any specific circulating system for the cooling medium. 75

For the purpose among other things of compactness in structure there is what is termed a conduit portion 18 and a compression chamber portion 19, the former having 80 passage 20 therethrough and the latter having chamber 21 formed therein by a diaphragm 22 disposed between the annular flanges 23. The concavity 24 below the diaphragm 22 affords a greater extent of travel 85 of the movable member 25 in its opening movement of the valve 26 which is pivoted in the conduit 18 and constantly urged to closed position by the pull spring 27 anchored at 28 and attached to the valve 90 at its other end. For downward movement of the valve 26 link 29 is in engagement with pin 30 and is pivotally attached at 31 to stem 32 which is fixed to member 25. The stem 32 is slidably 95 mounted in bore 33. The inlet passage 34 communicates at its outer end with pipe 35, and is connected with the interior of the exhaust manifold (not shown) or other preferred source of fluid under compression. 100

The temperature responsive means for establishing communication between the source of fluid pressure and said pressure responsive means may be of any desired form. Preferably there is employed what 105 is known as a hermetically sealed thermal element 36 of the type comprising a sheet metal hollow spun construction having a

number of diaphragms with chambers 37 containing a liquid of high coefficient of expansion, such as alcohol, or a more volatile liquid, if desired. At is lower end there is 5 a boss 38 fixed centrally to the outer end wall of the element 36 and supported by rod 39 which is fixed laterally to the inner wall of the conduit 13. The head 40 of the element 36 is in threaded engagement with 10 stem 41 which is slidably mounted in bore 42 in the portion 43 of the port 19. The stem 41 at 44 is provided with an annular groove. At 45 a slot is formed for the escape of fluid under pressure. The bore 42 and 15 the inlet passage 34 intersect near the upper end of the former and the outer end of the latter. On sufficient expansion of the liquid in the element 36 the stem 41 will be forced upwardly enough for the annular recess or 20 groove 44 to register with the passage 34, when the force of the fluid under pressure will move the diaphragm 22 and the movable parts below it downwardly, and will result in the valve 26 being opened and held 25 open during the period of time that the fluid pressure is greater than the strength of the pull spring 27. When these conditions are reversed the valve 26 will be closed.

In operation, when the engine is first 30 started the cooling medium is cool or cold, and the thermal element 36 is in a contracted condition, the upper end of the stem 41 preventing the ingress of fluid under pressure into the passage 34 from the pipe 35, which latter preferably communicates with 35 the interior of the exhaust manifold (not shown). During this period of time the valve 26 is closed, and the cooling medium cannot pass to the radiator 7 but leaves 40 the conduit 13 through nipple 14 and passes through the tube 17 and enters the intake side of the pump 8, and through tube 10 back into the water jacket 4.

It will be noted the thermal element 36 45 is positioned in the conduit so as to be subjected to the heated medium, which rapidly will impart sufficient of its heat to expand the element 36, and thereby reestablish communication between the pipe 35 and the 50 chamber 21. This results in opening the valve 26 and permits the passage of the heated medium to and through the radiator during the continuance in motion of the engine. When the engine is stopped the pressure 55 of the exhaust through the pipe 35 will cease, permitting the diaphragm 32 and its parts to rise, whereupon the springs 27 will close the valve 26.

By showing and specifically describing one embodiment of my present invention I do not intend to restrict the range of equivalents not made necessary by the prior state of this art.

Having thus fully described my invention, what I claim as new and desire to secure by Letters-Patent, is—

1. In a temperature regulator for the cooling medium in an internal combustion engine, a circulating system for the cooling medium, a source of fluid pressure resulting from the engine exhaust, pressure responsive means for regulating the flow of the cooling medium in the circulating system, and temperature responsive means for establishing communication between said source of fluid pressure and said pressure responsive means to operate the latter.

2. In a temperature regulator for the cooling medium in an internal combustion engine, a circulating system having a valve and a thermal element therein, pressure responsive means in operative engagement with said valve, a source of fluid pressure, a port in the fluid pressure line communicating with said pressure responsive means, and a slide valve connected to and operated by said thermal element and intersecting said port, said slide valve in one position adapted to close the pressure side of said port and to vent the other side thereof and adapted to be moved by said thermal element to open said port and to close said vent.

3. In a temperature regulator for the cooling medium in an internal combustion engine, a circulating system having a valve and a thermal element therein, pressure responsive means in operative engagement with said valve, a source of fluid pressure, a port in the fluid pressure line communicating with said pressure responsive means, and a slide valve connected to and operated by said thermal element and intersecting said port, said slide valve having an annular groove therein and a slot in one side thereof, said groove adapted to be brought to register to open communication through said port, and said slot, when said groove is out of register adapted to vent that side of said port communicating with the pressure responsive means.

In testimony whereof I affix my signature in the presence of a witness.

CHARLES L. RAYFIELD.
